(57) **CLAIM**

The ornamental design for a helmet visor, as shown and described.

DESCRIPTION

FIG. 1 is a front perspective view of a helmet visor showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view of the helmet visor taken in the direction of line 8-8 in FIG. 2; and,

FIG. 9 is a cross-sectional view of the helmet visor taken in the direction of line 9-9 in FIG. 2.

The broken lines in the figures depict portions of the helmet visor which form no part of the claimed design.

The dot-dash broken lines in the figures represent a boundary of the claimed design and form no part thereof.

1 Claim, 9 Drawing Sheets
